UNITED STATES PATENT OFFICE.

WILLIAM C. RANDS, OF DETROIT, MICHIGAN, ASSIGNOR TO RANDS MANUFACTURING COMPANY, OF DETROIT, MICHIGAN, A CORPORATION OF MICHIGAN.

GLASS-CLIP-PLUG ASSEMBLY.

1,243,445.

Specification of Letters Patent. Patented Oct. 16, 1917.

Application filed April 17, 1916. Serial No. 91,670.

To all whom it may concern:

Be it known that I, WILLIAM C. RANDS, a citizen of the United States of America, residing at Detroit, in the county of Wayne 5 and State of Michigan, have invented certain new and useful Improvements in Glass-Clip-Plug Assemblies, of which the following is a specification, reference being had therein to the accompanying drawings.

10 This invention relates to an improved glass clip plug assembly, and refers more particularly to a construction adapted for use in connection with windshields for automobiles or the like.

15 Among the objects of the invention are to provide an improved construction for locking in position the clip employed for holding the glass into position in the frame and for giving a finished appearance to the end 20 of the frame tube; to provide a construction in which a relatively light securing member, such as a stamping or punching of any metal of the gage desired, may be employed; to avoid the necessity of pinning or riveting 25 this securing member in position; to provide a construction which shall be less expensive than those previously employed for this purpose, and which will do away with the unnecessary weight of the solid metal 30 plugs previously employed; to provide a construction in which the securing member is inserted through slots or holes punched opposite each other in the tube, in such a manner as to provide a ledge or shelf on the 35 inner side of the tube; and in general to provide an improved and simplified construction of the character referred to.

The invention further resides in various features of construction and combinations 40 and arrangements of parts as will more fully hereinafter appear.

In the drawings:

Figure 1 is a vertical section through a corner of a wind-shield showing my invention employed therein;

Fig. 2 is a cross section on the line $\alpha-\alpha$ of Fig. 1;

Fig. 3 is a view similar to Fig. 1 showing a slightly modified construction; and

50 Fig. 4 is a view similar to Fig. 2 showing the construction illustrated in Fig. 3.

Describing in detail the particular embodiment of my invention shown in the drawings, A designates the vertical tube of 55 the frame, and B the glass panel, the edge

portion C of which is received in the groove D of the frame member. At the end of the tube A there is employed a glass clip E, which serves to both hold the glass into its position in the frame and to lend a finished 60 appearance to the end of the frame tube.

In detail, this clip comprises a main body portion F adapted to fit over the end of the tube A, this body portion being preferably of the same shape as the tube and being provided with a projecting lip G which extends over the glass panel B and holds the latter in position. It has been customary in securing the clip in position to employ a solid metal plug drilled somewhere on the side 70 for the purpose of inserting a rivet or pin for holding the clip in position on the tube. This construction was not only expensive but since it is customary to employ four of these 75 clips on every divided windshield, considerable unnecessary weight is produced.

The present invention contemplates a construction in which the solid metal plug is done away with, and a relatively light stamping or punching H employed as the 80 abutment member, which permits of screwing home into place the screw J which draws the clip into position on the frame. This stamping or punching H is first drilled and tapped or punched and tapped, and then 85 inserted into the tube through apertures L and L' punched on the opposite sides of the tube. In punching these apertures, the metal is forced inwardly so as to provide inwardly-projecting flanges M and M' which 90 receive the ends of the stamping or plug member H, and form a shelf or ledge upon which the latter rests. The clip member B is then slipped over the end of the tube A and the screw J screwed down through the 95 stamping or plug member H so as to draw the clip member firmly into position. When thus assembled, the lower end of the clip member projects down beyond the plane of the apertures L and L', completely covering 100 these apertures and the ends of the plug member and giving a finished appearance to the end of the frame.

In Figs. 3 and 4, the construction is substantially the same as that shown in Figs. 105 1 and 2, except that the main body portion F of the clip is circular in form to correspond with the circular form of the tube A. It is obvious that the shape of the plug will be governed by the inside shape of the tub- 110

ing, and that the shape of the main body portion of the clip will be similarly governed. The tubing can, of course, be made in a variety of styles, such as round, square, oval, pear-shaped, rectangular, etc. The invention, however, is not limited to any specific shape or shapes or to any details of construction except as specified in the appended claims.

10 What I claim as my invention is:

1. In a glass clip plug assembly, the combination with a frame member having an apertured side wall, of a glass clip having a portion fitting over the end of the frame member, a securing member for said glass clip and a plug member engaged by said securing member, said plug member being inserted through the aperture in the frame member and means for holding the plug member in position in the frame member.

2. In a glass clip plug assembly, the combination with a frame member having an apertured side wall, of a glass clip having a portion fitting over the end of the frame member, a securing member for said glass clip and a plug member engaged by said securing member, said plug member being inserted through the aperture in the frame member, and said clip having a portion extending down over the apertured portion of the frame member.

3. In a glass clip plug assembly, the combination with a frame member and a glass clip, and means for holding said clip in position including a plug member positioned within the frame member, means for securing the clip to the plug member, and a ledge projecting on the inside of the frame member for receiving said plug member.

4. In a glass clip plug assembly, the combination with a frame member having slots formed opposite each other and the metal forced inward to provide a ledge or shelf on the inner side of the frame member, of a plug member inserted through said opening and resting on the ledge or shelf, a glass clip extending over the end of the frame member and a member adjustably securing said clip member to said plug member.

5. In a glass clip plug assembly, the combination with a frame member having oppositely positioned slots or holes, an inwardly extending projection on the inner side of the frame member, a plug member engaging said projection and a glass clip member having a portion extending over the ends of the plug member in the assembled position of the parts and means for securing the clip to the plug member.

In testimony whereof I affix my signature.

WILLIAM C. RANDS.
